UNITED STATES PATENT OFFICE.

FRANK WILCOMB, OF PAWTUCKET, RHODE ISLAND.

CIRCULAR-KNITTING MACHINE.

1,086,968.

Specification of Letters Patent.

Patented Feb. 10, 1914.

Original application filed October 2, 1912, Serial No. 723,522. Divided and this application filed June 26, 1913. Serial No. 775,938.

To all whom it may concern:

Be it known that I, FRANK WILCOMB, citizen of the United States, residing at Pawtucket, Rhode Island, have invented 5 certain new and useful Improvements in Circular-Knitting Machines, of which the following is a specification.

The subject matter herein disclosed is a division of that contained in my application for Letters Patent of the United States 10 #723,522, of October 2, 1912, and concerns particularly sinker and web-holder mechanism and associated devices, and the invention consists in the features and combination and arrangement of parts herein- 15 after described and particularly pointed out in the claims.

In the accompanying drawings Figure 1 is a side view of a knitting head embodying 20 my invention; Fig. 2 is a vertical sectional view of Fig. 1; Fig. 2^a is a detail; Fig. 3 is a side view of the thread cutter, clamp and needle evener and the supporting arm for said parts, the view being of the opposite 25 side to that shown in Fig. 2; Fig. 4 is a detail view; Fig. 5 is a vertical section looking from the right of Fig. 2; Fig. 6 is a bottom plan view of the thread cutter, thread clamp, needle evener and their supporting arm; Fig. 7 is a plan view of the knitting head; Fig. 8 is a sectional view substantially on the radial line 16 of Fig. 7 through the presser wheel and associated parts; Fig. 9 is a view of my improved sinker; Fig. 10 30 is a sectional view of my improved sinker bed; Fig. 11 is a view of a web holder; Fig. 12 is a view of a different form of sinker in place in its bed.

My machine in the form chosen to illustrate my invention includes as knitting elements independently operated spring needles 1, independently operated sinkers 2, to feed the yarn to the needles, independently operated sliding web holders 3, which 45 hold the fabric from being carried up when the needles are elevated to take the thread, and which also assist in casting off old loops, and pressers 4-4' for pressing the needle beards.

50 *Presser mechanism.*—The presser wheels 4-4' are set with relation to the needles and sinkers, as shown in Figs. 7 and 8, and at this point the sinkers are always pro-

jected inwardly between the needles far enough to sink the required amount of yarn 55 which is always sufficient to allow the lower nose to be inside the needle row allowing the presser to roll on the needles behind this nose as in Fig. 8.

The pressers 4, 4', comprise preferably 60 wheels which are adjusted by their rods, screw threaded at their ends, and engaged by jam nuts *k*, springs under adjustment of nuts *k'* forcing the pressers inwardly to exert a yielding contact with the needles. 65 The rear presser is made up of a plain wheel and a notched lower wheel *l*, Fig. 8, the upper wheel having fixed thereto a pin *m*, turning in a bushing *m'*, mounted in the block *o* and held by a set screw *n'*, while the 70 lower wheel has a bushing fixed thereto and mounted to turn in a bracket *p* extending from another adjusting rod *q*, which has a spring and adjusting nut for adjustment like that above described. These two presser 75 wheels are mounted one above the other but their supporting and adjusting means are arranged side by side in the same plane and in a bracket *r*, attached to the sinker ring. The bustling *o* is of large enough internal 80 diameter to allow one presser wheel to be adjusted in relation to the other so that the notches in one wheel may be exposed for tucking as is well understood by knitters. In the present instance I have shown the 85 lower presser wheel as notched.

I have shown two pressers disposed at different points about the needle circle for reciprocating work, one being effective on one stroke and the other on the other stroke 90 of the cylinder. In plain circular work of course only one presser would be effective, for instance the needles would miss the front presser because the call jacks do not throw the needles up high enough on the 95 rising side of the advancing cams to bring them into contact with the presser, but having been lifted by the advancing cam to be moved down by the draw cam they will traverse a path to have their beards pressed 100 by the presser.

Thread carriers.—The thread carriers are shown at 94, Figs. 5 and 7, there being a number of these for introducing different kinds of thread, as will be hereinafter described. These carriers consist of arms

having openings or eyes at their ends for the passage of the threads, and each arm is pivotally mounted at 95 on the sinker cam ring 72 so that it may be raised and lowered to remove or introduce its thread, and for this purpose the tails of the thread carriers are in line vertically with levers 96 pivoted to a housing 97, these levers in turn being operated by levers 98 also pivoted to the 10 housing and operated through wires 98', Figs. 1 and 5, running to the pattern mechanism like the wires f' of the Hemphill Patent 933,443. The thread carriers are lowered to their work by springs 99 when 15 allowed to do so by the pattern connections.

Sinkers and pressers.—I have designed a new form of sinker which will allow the pressing device 4 or $4'$ to be arranged outside of the needle row, and between the said 20 sinkers and the web holders, this arrangement being particularly adapted for use in a stocking machine having its space inside the needle row occupied by thread clamping and cutting mechanism, the arrangement being also adapted for other types of machine, as for instance, for making underwear. A 25 sliding sinker of ordinary form could not be employed on the outside of the needle row in conjunction with a presser device located wholly outside of the needle row because the 30 bed for an ordinary sinker would occupy all the space necessary for the presser device. I have therefore devised a form of sinker and a form and arrangement of the sinker bed 35 by which the sinker bed can be located above the place usually occupied by a sinker bed and thus leave space in which the presser device may be located.

My improved sinker comprises a stem a' , 40 Figs. 2, 5, 8 and 9, having a shank or shanks b' to engage the sinker cams above described, and an arm c' extending downwardly and forwardly from the stem and terminating in a nose of substantially ordinary construction. The stem being elevated in respect to 45 the work end or arm of the sinker enables me to employ a sinker bed which is elevated above the plane usually occupied by it, and this leaves space for the pressers 4 or $4'$ 50 which may thus be arranged in proper relation to the needles, sinkers and web holders, namely: in a plane between the sinkers and web holders and on the outside of the needle row. The sinker bed is of improved construction being grooved in its upper side 55 Fig. 10 for the stem of the sinker and grooved at d' in its lower side for the work arm or lower nose carrying extension, with a vertical opening at e' in line with the upper 60 and lower grooves through which the depending arms of the sinkers extend.

The upper grooves of the sinker bed lying in a circle of large diameter in respect to the needle circle provide outlying portions having thick walls between the grooves for

guiding the stems of the sinkers, and sustaining lateral thrust, while the lower slots being nearer the needle circle than the outlying portions have thin walls but these are sufficiently strong for guiding the lower 70 arms of the sinkers which are not subjected to the lateral thrust of the cams. The shanks of the sinker stems for engagement with the cams being at the outer ends of the sinkers low angle cams can be used. The 75 sinker in its best form will have its stem projecting forward of the depending arm and running in a groove h forming a continuation of the upper groove. This extension will prevent the sinker from tipping 80 downwardly at its work or nose end while upward tipping will be prevented by the lower arm of the sinker bearing up against the under side of the sinker bed. This form of sinker bed provides for keeping oil, lint 85 or other matter from passing from the sinker cams and grooves of the sinker bed to the fabric.

The removal and insertion of the sinkers is easily effected by raising the rear shank 90 portion and drawing it upward and outward from the machine.

As a modification of the sinker I may, as shown in Fig. 12, form it in two parts, an upper stem portion a'' and a lower work 95 portion, these being connected together by an arm or nib c'' on the upper stem portion fitting in a notch in the lower work portion. In this case I would use a plate s fixed under the sinker bed to hold the work portions of 100 the sinkers in the grooves.

The arrangement of the presser device outside the needle row in a stocking machine, as above stated, leaves the central portion of the machine free for the arrangement of the 105 thread cutter and clamp, but furthermore an inside presser would be open to objections other than that of occupying the center of the machine necessary for the location of the other devices. For instance, in making a 110 heel pocket, at which time the fabric gathers up, or in case the fabric for any reason gathers up, as in the case of a defective needle, an inside presser would be liable to be forced away from the needle and not perform its 115 function. In my arrangement with the presser outside the needle row this objection is avoided. The presser wheel being located under the sliding sinkers, as above described, and the sinkers being always advanced at the point where the sinking takes place, the said sinkers serve as a guard to prevent anything coming between the 120 presser and the needles.

Web holders.—My improved web holder 125 Figs. 2, 5, 8 and 11, has a lower extension t working in a groove t' of a ring u secured to the top of the needle cylinder. This groove extends circumferentially of the ring, and it is open throughout, having no radial 130

grooves for these lower extensions. The upper side of this groove is ground and affords a bearing to hold the web holders against tipping. The upper work end, or extension 5 of the web holder runs in radial grooves at the top of the ring but these grooves are shallow, affording rigidity to the guiding walls and making the construction comparatively inexpensive to manufacture. By this form of web holder and ring the upper work-end is bottomed in the upper grooves while the lower extension slides on the plain upper side of the circumferential groove, thus firmly and accurately guiding the web holder.

The web holder bed *w* is clamped by screws 109, Figs. 2 and 11, to the cylinder, and the web holder cam ring 110 which overlies and is supported by the bed, is held against circumferential displacement by adjusting screws 111 passing through ears 112 on the ring and bearing upon the sides of the front standard 101.

Shifting sinker organization.—The sinker cam ring 72 is composed of upper and lower members screwed together, between which the sinker bed is located. This sinker bed has gear teeth 115 into which meshes the split gear 116, Fig. 2, clamped on the recessed end 117 of the vertical shaft 118, which carries a gear 119 at its lower end meshing with the gear 8' on the needle cylinder. The sinker supporting ring 72 is carried or supported by a bracket 120 turnable on the upper end of the standard 121 which extends up from the base of the machine and through which standard the vertical shaft 118 extends. This bracket is also movable vertically and it carries the shaft with it to cause the flange 122 forming part of the split clamp 123, which holds the gearing to the shaft, is pinned to the said shaft. Below the bracket a yoke or collar 124 is located connected by a link 125 with an eccentric or crank 126 on a shaft or pin 127 journaled in the standard and operated by a handle 128. When this handle is turned down from the position shown in Fig. 2, the yoke will be lifted to raise the bracket, together with the sinker ring, supported thereby, to the position indicated in dotted lines at *w'*, Fig. 2, and then the sinker ring, together with all the parts carried thereby, may be swung aside in the direction of the arrow *y*, Fig. 7, this turning movement being about the axis of the shaft 118 as a center. This will enable access to be had to the cylinder, needles, web holders and their cams. At all times the gear connection between the cylinder and the sinker organization will be maintained so that these will be operated in unison. The yoke 124 is kept from turning by a spring pin 129 mounted in the standard 121, the spring 130 being housed in the hollow pin and bearing at its

lower end upon the block 131 supported on a pin 132 fixed in the standard. The upper end of the spring pin fits between the ears of the yoke as shown. A dowel pin 133 aids in centering the yoke. In swinging the 70 sinker organization back to working position it is arrested by a stop 134 fixed to the standard or post 101, which is engaged by a projection 135 on the sinker ring. When so arrested the sinker ring has a notch registering with the stop or registering pin 137, and thus by lowering the sinker ring the notch thereof will be engaged by the pin 137 and the sinker ring will be held centrally in respect to the axis of the needle cylinder and 80 web-holder organization.

It will be observed that the lower part of the sinker ring encircles the web holder organization fitting closely, when lowered to working position about the cam ring 110 of 85 the web holders. This centralizes the upper end of the cylinder and the web holder organization and furnishes lateral support for these parts and insures the true running of the needle cylinder. In the case of a small 90 diameter machine and a tall cylinder very small variations in the bearing at the base of the cylinder will be multiplied at the top of the cylinder resulting in a wobbling motion at this point and uneven knitting if no 95 provision were made to avoid this. With the sinker organization arranged and supported by the standards 101 and 121, and closely surrounding the parts at the top of the revolving cylinder the latter will be 100 made to run true.

Thread cutter, clamp, and needle evener.—As is customary in stocking machines which make the heel and toe, I provide on the inside of the needle row a thread cutter and a 105 thread clamp. Referring to Figs. 2, 3, 5 and 7, this cutter includes a fixed blade 138 and a movable blade 139 both mounted on a bracket 140 which is pivoted on a standard 141 fixed to the sinker ring. The movable blade is pivoted at 142 and is operated through a rod 143, connected to a disk 144 pivotally mounted on the standard at 145, the arm 146 of said disk being operated by a rod 147 engaging therewith at a point in 110 line with the axis about which the sinker ring is turnable. The supporting bracket may be turned upwardly about its pivot 145 to remove the same from over the needle cylinder and thus remove the parts carried 120 thereby from within the sinker ring. This bracket also carries the clamp for the loose ends of the threads severed by the cutter, this clamp comprising a rigid clamping member 150, Fig. 3, and a movable clamping member 151, the latter being of grating form, Fig. 6, and being arranged below the fixed solid member to shed dust, lint, &c., which might otherwise interfere with the clamping members coming close together. 125 130

The thread is guided to the clamping members by a guide or guard plate 152. The movable clamping member is carried by a block 153, Figs. 3, 4 and 5, on the shaft 154 to which the movable cutter blade is fixed, said block being turned by a pin 155, Fig. 4, on the shaft engaging the block, provision for slight lost motion being made between the pin and the surface of the block with which it contacts. The movable clamping member is held up by a spring 156. Now, when the movable cutter blade is lowered to receive the thread between it and the fixed cutter blade, the movable clamping member will be lowered to receive the thread between it and the upper fixed member, the thread being guided in between these parts by the guide 152. The movable cutter blade now rises allowing the clamp to be set first to hold the thread, and then the cutter continuing its movement upward will sever the thread, leaving the loose end in the clamp.

I provide on the inside of the needle row a needle evener 157, Figs. 3, 5 and 7, to even up any needle which may have been bent, this evener being operative adjacent the point at which the yarn is sunk to the needle, as shown in the plan view, Fig. 7. It lies slightly below the plane of the sinkers, Fig. 5, and is carried by an arm 158 pivotally mounted at 159 to the underside of the supporting bracket. The arm is bent upwardly and extends over the sinker ring, where it is engaged by a catch at 160 by which it is locked in position, and this arm therefore acts as a lock to hold the bracket 140 down in working position with all the parts carried thereby properly located within the needle circle. To swing the bracket 40 up, the evener carrying arm is turned from under the catch in the arrow direction, Fig. 7, and on swinging the bracket upwardly in the direction of the dotted arrow, Fig. 3, the clamp, cutter and needle evener go up with it, above and to one side of the needle row, to allow access to the interior of the needle cylinder or to allow the sinker organization to be shifted aside in getting access to the web holder organization.

50 In the operation of the clamp and cutter, when the thread carrier is raised the thread extends from this to the needle last supplied and is carried around by revolution of the needle cylinder and under the guide which directs it between the clamping members. After the thread is severed the loose end is held by the clamp until again introduced by the thread carrier.

It will be seen from the foregoing description that the sinker ring supports various devices, the cutter and clamp, needle evener, the thread guides, pressers and part of the connections for adjusting the sinker cams and when the sinker ring is swung

aside all the said parts move therewith and the act of moving the sinker ring back to normal position establishes the necessary connection for operating the thread carriers and adjusting the sinker cams.

I claim as my invention:

1. In combination in a circular spring needle knitting machine, a cylinder, independently operated needles, sinkers and web holders outside the needle row, beds in which said sinkers and web holders slide, a presser device radially adjustable outside the needle row to engage the needle beards in succession and arranged between the sliding sinkers and web holders, and means for effecting relative movement between the needle cylinder and presser circumferentially of the cylinder, substantially as described.

2. In combination, spring needles, web holders and sinkers, a presser outside the needle row and between the sinkers and web holders, a bed above the presser, said sinkers having an upper heel carrying stem sliding in said bed, and a lower yarn sinking portion connected thereto, and cams engaging the heel of the sinkers, substantially as described.

3. A sinker bed for a knitting machine having upper and lower radial guiding slots to receive upper and lower portions of a sinker and with an opening through the bed connecting said upper and lower slots to receive the portion of the sinker which connects said upper and lower portions, substantially as described.

4. In combination a sinker bed for a knitting machine having upper and lower slots, with an opening through the bed connecting the said upper and lower slots, and a sinker having an upper heel stem slidable in the upper slot and a lower yarn sinking portion slidable in the lower slot and a connecting portion extending through the said opening, substantially as described.

5. A sliding sinker or thread measurer for sinking the yarn across the stems of the needles, said sinkers having a slidable cam operated stem, said stem being arranged in a higher plane than the yarn sinking portion which is connected to and operated thereby, whereby the sinker may be used with a beard presser operating between the plane of the said yarn sinking portion and the plane of movement of the web holder.

6. In combination, spring needles, web holders and sinkers, a presser between the sinkers and web holders, a bed above the presser slotted in upper and lower planes, sinkers having stems sliding in the upper slots and nose carrying arms sliding in the lower slots, substantially as described.

7. In combination, spring needles, web holders and sinkers, a presser between the

sinkers and web holders, a bed above the presser slotted in upper and lower planes, sinkers having stems sliding in the upper slots and nose carrying arms sliding in the lower slots, said arms depending from the intermediate parts of the stems, the front and rear ends of the stems finding bearings in the bed, substantially as described.

8. In combination in a knitting machine, 10 a rotary cylinder, a sinker supporting element surrounding and centralizing the cylinder at its upper end, said sinker element being shiftable to and from its normal position surrounding the cylinder by lifting it 15 and moving it to one side, and means for supporting the sinker element from the base of the machine, substantially as described.

9. In combination in a knitting machine, 20 a needle cylinder, web holders, cams therefor, sinkers, and a sinker supporting element movable from position in relation to the web holders and cylinder to expose the web holders, and means for supporting the sinker element from the base of the machine, 25 substantially as described.

10. In combination in a knitting machine, 30 a rotary cylinder, needles, a sinker organization comprising sinkers, a sinker bed, a sinker cam ring, driving means for the cylinder and sinker bed, a support for the sinker organization connected with the base of the machine, means for holding the sinker organization elevated in relation to the cylinder, said sinker organization being 35 shiftable laterally from normal position by turning it about the axis of its driving means, substantially as described.

11. In combination in a knitting machine, 40 a rotary needle cylinder, needles, a sinker organization consisting of a sinker bed and a sinker cam ring, a support extending up from the base connected with the sinker organization, said sinker organization being shiftable vertically and laterally from normal position in relation to the cylinder, and driving means for the cylinder and sinker cam ring, maintaining its connection with said parts in all positions of the sinker organization, substantially as described.

50 12. In combination in a circular knitting machine, a rotary cylinder, needles, a sinker organization consisting of sinkers, a sinker bed, a sinker cam ring, said sinker organization being shiftable from normal position in 55 relation to the cylinder, driving means for the cylinder, a vertical shaft, gearing between said shaft and the cylinder, gearing between said shaft and the sinker cam ring, the shifting movement of the sinker organization taking place about the axis of said shaft, substantially as described.

13. In combination in a circular knitting machine, a rotary cylinder, a sinker organization comprising sinkers, a sinker bed, a

sinker cam ring, a standard supporting the 65 sinker organization from the base of the machine, a driving shaft for the sinker organization extending through the standard, gearing between said drive shaft and the sinker organization, and means for raising 70 the sinker organization, said sinker organization being shiftable laterally and about the said shaft, substantially as described.

14. In combination in a circular knitting 75 machine, a cylinder, needles, a sinker organization consisting of sinkers, a sinker bed and a sinker cam ring, said sinker organization being laterally shiftable away from normal position concentric with the 80 needles, and a needle evener inside the needle row and shiftable vertically in relation to the needles and sinker organization and supported by the latter, substantially as described.

85 15. In combination in a circular knitting machine, a cylinder, needles, a sinker organization consisting of sinkers, a sinker bed, a sinker cam ring shiftable laterally in relation to the needle cylinder, a thread clamp and a cutter inside the needle row and a vertically movable support carrying said clamp and cutter, said support being mounted on the sinker cam ring, substantially as described.

95 16. In combination in a circular knitting machine, a cylinder, needles, a sinker organization consisting of sinkers, a sinker bed, a sinker cam ring shiftable by turning it to one side about a center, a thread clamp and cutter within the needle row supported on the shiftable sinker organization, and a connection for operating the cutter and clamp, extending from the center about which the sinker organization turns, substantially as described.

100 17. In combination, in a circular knitting machine, a cylinder, needles, a sinker carrying ring shiftable laterally of the cylinder, and thread carriers supported on the sinker 110 ring, substantially as described.

115 18. In combination in a knitting machine, a cylinder, needles, sinkers, a sinker ring laterally adjustable to and from the cylinder, thread guides mounted on the sinker ring, connections for operating the thread guide automatically, operative relation between said thread guides and the said connections being established or broken by the swinging of the sinker ring to or from normal position, substantially as described.

120 19. In combination in a circular knitting machine, a cylinder, needles, a sinker carrying ring shiftable laterally of the cylinder and a presser for the needle beards supported on the shifting sinker ring, substantially as described.

125 20. In combination in a circular knitting

- machine, a sinker ring shiftable laterally of the cylinder, a yarn severing and clamping means attached to the ring and shiftable therewith, substantially as described.
- 5 21. In combination in a circular knitting machine, a cylinder, knitting elements, a sinker organization comprising sinkers, a sinker bed and a sinker cam ring, sinker cams, connections for adjusting the sinker 20
10 cams, said sinker organization being shiftable to and from operative relation with the cylinder and knitting elements and into and out of operative relation with the operating
15 connections for the sinker cams, substantially as described.
22. In combination in a circular knitting machine, a cylinder, knitting elements including sinkers, a sinker bed, a sinker cam ring shiftable laterally in relation to the cylinder, a registering device for the sinker cam ring, said device engaging the sinker cam ring when the latter is lowered into place, substantially as described.

In testimony whereof, I affix my signature in presence of two witnesses.

FRANK WILCOMB.
